P. F. SPERY,
RADIATOR FOR MOTOR VEHICLES AND THE LIKE,
APPLICATION FILED MAY 11, 1918.

Patented Sept. 16, 1919.

UNITED STATES PATENT OFFICE.

PHILMORE F. SPERRY, OF CHICAGO, ILLINOIS.

RADIATOR FOR MOTOR-VEHICLES AND THE LIKE.

1,316,199.

Specification of Letters Patent. Patented Sept. 16, 1919.

Application filed May 11, 1918. Serial No. 233,844.

To all whom it may concern:

Be it known that I, PHILMORE F. SPERRY, a citizen of the United States, and a resident of the city of Chicago, in the county of Cook and State of Illinois, have invented a certain new and useful Improvement in Radiators for Motor-Vehicles and the like; and I do hereby declare that the following 5 description of my said invention, taken in connection with the accompanying sheet of drawings, forms a full, clear, and exact specification, which will enable others skilled in the art to which it appertains to make and use the same.

15 My invention relates generally to improvements in radiators; and it consists, essentially, in the novel and peculiar combination of parts and details of construction, as hereinafter first fully set forth and described and 20 then pointed out in the claims.

The object of this invention is the production of an efficient and serviceable radiator for cooling water in internal combustion engines, such as are used in automobiles, motor 25 trucks, traction engines, launches, aeroplanes, and the like, in which the cylinders are cooled by water contained in jackets surrounding the cylinders, and which water abstracts heat from the cylinders and is then 30 conducted to a radiator, so-called, of cellular construction, in which metallic surfaces are exposed to currents of air passing through the cellular structure, and thereby absorb heat from the water, which water circulates 35 between the engine and the cooler, and is constantly used over and over again.

Radiators of this nature are more or less expensive to produce, being usually made of copper or brass owing to high efficiency in 40 heat conducting, and any improvement which has a tendency to reduce the cost of manufacture of the radiator, in view of the large quantity of radiators constantly required, even to a slight extent, is a desideratum. I believe that by the construction of 45 my improved radiator, as hereinafter set forth, I have reduced the cost of production, simplified the methods of manufacturing, and produced an article of superior merit.

50 In the drawings forming a part of this specification, Figure 1 is a front elevation of a radiator embodying my improvements, no attention being given in this figure to details of construction. Fig. 2 is a vertical transverse section on line 2—2 of Fig. 1. 55 Fig. 3 is an edge-view, and Fig. 4 a side ele-

vation of a strip of metal forming a part of the means which assist in the cooling effect of the radiator. Fig. 5 is an edge view, and Fig. 6 is a plan of one of the cross bars associated with the strips of metal shown in Figs. 3 and 4. Fig. 7 is an elevation of a portion of a unit comprising this radiator, the figure being approximately full scale. Fig. 8 is a sectional elevation on line 8—8 of Fig. 7. Fig. 9 is a front elevation of a series of units assembled; and Fig. 10 is a plan of the same. Fig. 11 is a sectional view of one of the units, on line 11 of Fig. 7. Fig. 12 is a strip of metal forming a part of the means which assist in the cooling effect of the radiator, slightly modified. Fig. 13 is a sectional plan detail of construction; and Fig. 14 is a like view on an increased scale, illustrating the temporary means for securing the cross bar to the vertical strip forming the heat conductor. Fig. 15 is a sectional view on line 11 of Fig. 7, drawn on a slightly increased scale and showing the two members of a core unit before being locked together. Fig. 16 is, 80 a sectional detail showing the connection of a cross bar to the modified form of the vertical bar illustrated in Fig. 12.

Like parts are designated by the same characters and symbols of reference in all 85 the various figures.

This radiator comprises, as illustrated in Figs. 1 and 2, an outer casing, A, open in front and rear, and containing the cellular core B, and an upper water chamber C, and 90 lower water chamber D, the water from the engine passing to the upper chamber through the water passages in the core B. to the lower chamber D, and thence back to the engine. This core comprises a series of 95 units each of which consists of two, thin, metallic plates or strips E, E_a, which are alike in contour; are formed of flat strips of proper width and length having each a series of corrugations 12, extending from 100 some distance from the longitudinal margins of the strips across the same, thereby leaving these marginal edges flat, as shown at 13, the corrugations starting and ending some distance from the ends of the strip to 105 afford flat surfaces 14, at these ends, the object of which will hereinafter appear. The apexes 15 of these corrugations are in the same plane, but are somewhat above the plane of the flat surfaces 13, 14, thereby 110 forming longitudinal shoulders 16, so that when two of these strips are placed face to

face, as illustrated in Figs. 7, 10, and 15, and in other figures, there is formed between the two strips a conduit 17, the ends of which when in assembled condition, terminate in, 5 and communicate with, the chambers C, D. These conduits are successively enlarged by the corrugations of the strips, and contracted or constricted where the corrugations meet, one of the objects of these corrugations 10 being to increase the cooling area of the strips, and to afford effective means for positioning the cross bars of the heat conductor, as will be later on described.

Between adjacent units of the cellular structure is placed means for assisting in the cooling effect of these units, which means comprise each a bar of metal 23, of proper width, which bar has slots at regular intervals, the slots 24, extending to one 20 half of the width of said bar 23. A series of cross bars J, of substantially rectangular contour have each a slot medially, extending to one half of the width of said cross bar. It has also at one end laterally extending 25 ears or lugs 26, the distance from out to out over these projections 26 being equal to the spaces 22, between adjacent units at their margins, and the portion 27 of said cross bar being equal to the distance between opposing units at the jointure 15 of the corrugations. These cross bars J are then placed 30 on the bars 23 with the slots in one engaging the slots in the other element, which brings the opposing margins of the bars 35 flush with the longitudinal margins of the bars 23, as clearly shown in Figs. 13 and 14.

The strips E, Ea, forming a unit are not of the same width, the strip E being narrower than the strip Ea, a condition clearly 40 illustrated in Fig. 15. The wider strip has its longitudinal margins bent at right angles, as at 18, to receive the narrower strip E face to face, after which the upstanding ledge 18 is turned down upon the flange 19 45 of the member E and forced into close contact therewith, thereby securely locking the two members E, Ea, at their longitudinal marginal edges.

Two metallic plates G, H, in properly 50 spaced relationship, are provided with slotted apertures 20, the number of which corresponds to the number of units employed, each one of these slots receiving a unit, the ends of the units extending above the outer 55 planes of the plates G, H, as indicated at the left of Fig. 9, and are bent over the plates as shown at 21, thus securely uniting the parts, said plates G, H, resting upon the uppermost and the lowermost corrugations 60 to prevent displacement thereof.

After the units have been secured to the plates G, H, the heat conductors I are pushed into the spaces 22 between adjacent units, where the lateral lugs 26 strike the longitudinal shoulders 16, of the members E, Ea, 65

and the marginal edges 27 enter the V-shaped crotch between adjacent corrugations, and thereby locate these conductors with their outer edges flush with the longitudinal edges of the unit members. In this condition, a 70 now assembled core is ready for the acid dipping bath, and then into a bath of molten solder, which so thoroughly unites the parts as to make a homogeneous structure of the same ready for being placed into, and 75 soldered to the casing A.

In order to prevent displacement of the cross bars J in handling before, and while being inserted into the core, I place the bars 23 and the cross bars J into a suitable chuck, 80 and then clench the ends of the cross bars adjacent the slots therein upon the strips 23, as illustrated on a magnified scale in Fig. 14, which sufficiently holds them together until they are finally permanently united by 85 the solder in the solder dipping bath.

It may now be noted that by locking the marginal seams of the units in the manner set forth, these seams and joints are so perfectly closed that scarcely any solder can 90 enter the same, and that the elements 23 and J fit so closely between the units as to require only a trifle of solder to complete the union, so that there is less solder employed in the construction of this radiator core than 95 there is required in any other radiator of the same capacity with which I am acquainted, it being a fact that there is in this radiator at least 2 lbs. less solder than in others of the same size, which at the present high 100 cost of solder amounts to a material saving in the cost of manufacture. Another advantage of construction resides in the fact that the elements 23, J, are rectilinear and right angular, that is to say, the bars 23 105 are vertically, and the cross bars horizontally disposed, so that there can be no compression or displacement of the parts when the structure is placed into a clamp so that the core can be handled for dipping. This 110 clamp is on the plan of a frame similar to a printer's chase, and has movable means pressing on the sides of the core for holding it tightly in the frame, a matter which in radiators having hexagonal or bee-cell construction causes elongation of the cells and thereby disarrange the parts, the opening of 115 seams and joints, and the absorption of much solder flowing into the cells and seams and retained therein when the core is lifted 120 out of the bath of molten solder.

In forming the corrugations in the strips E, Ea, a shortening of the strips takes place which reduces the length thereof, and necessitates a compression or increase in thickness of the metal at the longitudinal margins to cause them to correspond to the length of the strip after having been corrugated. In order to assist in the flowing of the metal at these margins, the corruga- 130

tions are gradually flattened at their ends as illustrated at 30, so as to merge into the shoulders 16. This construction is performed in suitable rolls and dies and accomplishes 5 the object without straining or rupturing the metal.

It will also be noted that the cross bars J engage the V-shaped portions of adjacent corrugations, thereby properly spacing the 10 cross bars and causing them to retain their proper position until they are finally integrally united to the bars 23 and the strips E, Ea, in the solder bath. While primarily the bars 23 and cross bars J are employed to prevent distortion of the core when being 15 clamped into the holding frame for dipping, they serve the additional and very essential object of increasing the cooling effect of the air passing through the spaces 22 between 20 the units by the heat conductivity of the metal of the bars and cross bars, which cooling effect is transmitted to the members E, Ea, of the core B.

The spaces between adjacent and connected strips E, Ea, afford vertical water passages 25 communicating with the water spaces C, D, in the casing A, while the spaces 22 between adjacent units form horizontal air passages through which air is brought in contact with 30 the metallic surfaces of the radiator units to abstract heat from the water passing through these water passages; and the greater the area of these metallic surfaces within a given space, the more efficient the 35 action of the cooling media will be. This increase of area is effected by corrugating the strips E, Ea, as described, while at the same time the crotches between the corrugations afford effective means for locating and 40 securely retaining the cross bars J in position.

In Fig. 12 I have illustrated a modified form, 23^a, of the bar 23, forming the vertical member of the cooling element I. This 45 strip or bar 23^a is of but one half the width of the bar 23, and instead of being slotted as at 24, its marginal edges are V-notched, as at 24^a, the cross bars J being applied to these bars 23^a, the same as heretofore described. It is notched at its two longitudinal edges to render the same reversible, 50 that is to say, that the cross bars may be applied to either edge, which facilitates assembling, and that while the notches on one 55 edge receive the cross bars, the notches at the other edge serve to clench the cross bars to the vertical bars at these notches. And it is to be noted that in this modified construction there is less metal used in the bars 23^a 60 than there is in the bars 23, which results in a slight saving in cost without noticeably affecting the efficiency of the device. These cooling elements are placed between the cell- 65 units at the outer margins thereof as indicated in dotted lines in Fig. 10, and may

be of any desired width, even to the full width of the strips E, Ea.

When employing the vertical bars 23^a for the filler or heat-conductor, it is necessary to form the slots 25 in the cross bars in the 70 margin opposed to the one illustrated in Figs. 13 and 14, to insure that the outer margins of these parts are alined, a matter which will be readily understood, by persons skilled in the art to which this invention 75 pertains.

I have hereinbefore employed the terms "heat-conductor" and "filler" interchangeably to designate the metallic structures placed into the spaces between adjacent 80 units which serve to assist the walls of these units being cooled, or in other words, to add to, by contacting with these walls, the metallic surfaces affected by the air passing through these spaces.

While I have hereinbefore described with considerable minuteness the preferred embodiment of my invention, I desire it to be understood that I am aware that changes in the details of construction may be made, 90 and parts omitted without departing from the scope of my invention as defined in the appended claims.

Having thus fully described this invention, I claim as new, and desire to secure 95 to myself by Letters Patent of the United States—

1. A radiator of the nature described, comprising a multiplicity of like units, each unit being constructed of two plates, said 100 plates having flat ends and flat longitudinal margins, said margins having shoulders, and a series of transverse corrugations intermediate said ends, the transverse terminals of said corrugations being gradually flattened to merge into the shoulders aforesaid, 105 said plates being placed face to face, the longitudinal edges of one plate overlapping the longitudinal edges of the other plate to afford permanent locking means, and means 110 for permanently uniting said units in spaced vertical relationship, said means including a top and bottom plate, said plates having spaced apart, slotted apertures, the ends of said units passing through said apertures, 115 the projecting portions of said units being folded over said top and bottom plates and clenched thereto; a core thus formed being permanently secured by dipping into a bath of molten solder.

2. In a radiator of the nature described, a core unit, said core unit comprising two plates, one of said plates having flat longitudinal margins, the other plate having like flat margins the edges of which are bent at 125 right angles, there being longitudinal shoulders adjacent the longitudinal margins of said plates, there being between said longitudinal margins transverse corrugations, 130 said corrugations being pronouncedly flat-

- 4
- tened at their ends and merging into said shoulders, said plates being placed face to face, the right angled bends at the longitudinal margins of one plate being bent over and clenched upon the flat margins of the other plate to afford locking seams, said plates being permanently united at their longitudinal margins by being dipped into a bath of molten solder.
- 10 3. In a radiator of the nature described, having spaced apart vertically disposed water tubes, a filler between adjacent water tubes, said filler consisting of a vertically disposed strip of metal, said strip having in one of its longitudinal edges a series of equally spaced notches extending approximately midway across said bar, and a series of cross-bars, each cross-bar being a metallic plate of a width corresponding to the spacing apart of the water tubes, and a length equal to the width of the vertical bar, said plate having a portion of its length reduced to afford shoulders, there being in said plates notches equal in depth to the notches in the vertical bar, a cross-bar being inserted into every notch in the vertical bar, the edges of the notches in the cross-bars being clenched

upon the vertical bar, the whole being permanently united by being dipped into a bath of molten solder.

4. A radiator of the nature described, including a cellular core, said core comprising a series of vertical, parallel-spaced units, each unit including two plates, each plate having flat side and end portions, a shoulder in each plate adjacent the longitudinal margins thereof, a series of transverse corrugations, said corrugations being approximately semi circular and adjoining one another to afford substantially V-shaped crotches between them, said corrugations being flattened at their ends and merging into the shoulders aforesaid, and filler bars between adjacent units, said filler bars including each a vertically disposed bar, a series of cross-bars secured to said vertical bar medially of their length, the ends of said cross-bars engaging the crotches between the corrugations of opposing units.

In testimony that I claim the foregoing as my invention, I have hereunto set my hand.

PHILMORE F. SPERY.
